UNITED STATES PATENT OFFICE

JOHN H. HINMAN, OF ST. LOUIS, MISSOURI, ASSIGNOR TO HEINE BOILER COMPANY,
OF ST. LOUIS, MISSOURI, A CORPORATION OF MISSOURI

BAFFLE OR WALL

Application filed April 11, 1927. Serial No. 182,858.

This invention relates to structures of the kind that comprise a plurality of tubes or other devices which pass through a baffle or wall arranged transversely of the tubes and 5 made up of tile, blocks or similar members set edgewise in superimposed relation.

The baffles or walls of this general type which have heretofore been used in water tube boilers, heat exchangers and economizers 10 were made up of tile or blocks of such construction that a tile designed for use with a baffle disposed at a certain angle to the tubes could not be used in the construction of a baffle disposed at a different angle to the tubes. 15 Nor could a tile designed for use with a straight baffle be used in the construction of a baffle provided with a curved portion. The baffles used in boilers and similar structures 20 vary in shape and in the angle at which the baffles are disposed to the tubes, and in many instances where a horizontal tube boiler is provided with a plurality of transverse baffles, each baffle is disposed at a different angle with 25 relation to the tubes of the boiler. Accordingly, the cost of constructing baffles of the general type mentioned is increased considerably by the necessity of keeping on hand a large number of baffle tile of different shapes, 30 suitable for use in the construction of straight and curved baffles and baffles disposed at different angles to the tubes. The work of erecting such baffles is also complicated by the necessity of using special tile for each baffle 35 of a particular angle or shape.

One object of my invention is to provide a 40 universal tile, block or member that can be used in the construction of baffles or walls of various angles and shapes.

Another object is to provide a baffle or wall 45 that is made up of tile, blocks or similar members which are adjustably combined and interlocked with each other in a novel manner.

Another object is to provide a baffle or wall 50 of the kind just referred to, in which the co-operating interlocking portions on the tile are of such design that substantially gas-tight joints will be produced between the tile.

And still another object of my invention is 55 to provide a novel method of constructing a baffle for a boiler or similar tubular structure.

To this end I have devised a baffle tile, block or element that consists of a member provided on two of its surfaces with portions that interlock with co-operating portions on adjacent tile, when said member is arranged in 55 alignment, in offset relation, or in reversed relation with said adjacent tile. To construct a baffle or wall from tile of the kind mentioned, the tile are laid up in horizontal courses or in vertical rows, and if it is desired 60 to change the shape or angle of the baffle, the adjacent tile are simply arranged in offset relation and in some instances the adjacent tile are arranged in reversed relation.

Figure 1 of the drawings is a vertical longitudinal sectional view of a water tube boiler 65 equipped with baffles constructed from baffle tile or blocks embodying my invention.

Figure 2 is a vertical longitudinal sectional view of a water tube boiler equipped with a 70 curved, transversely-disposed baffle constructed from tile or blocks embodying my invention.

Figure 3 is a fragmentary front elevational 75 view of a baffle or wall constructed in accordance with my invention, taken on the line 3—3 of Figure 1, looking in the direction indicated by the arrows.

Figure 4 is a perspective view of a tile or 80 block embodying my invention, adapted to be used in the construction of the intermediate portion of the baffle, i. e., the portion between the side edges of the baffle.

Figure 4^a is a perspective view of an intermediate tile provided on its top and bottom 85 faces and on its end faces with corrugations.

Figures 5 and 6 are perspective views, illustrating the end tiles or blocks that are used 90 to form the end portions of the baffle.

Figure 7 is an edge view of the baffle shown 95 in Figure 3, looking from the right hand end of said figure, one of the boiler tubes being shown in side elevation.

Figure 8 is a similar view, showing the tile 95 or blocks arranged to form a baffle provided with a curved portion.

Figure 9 is a similar view, showing the tile 100 or blocks in adjacent horizontal courses arranged in reversed relation, so as to produce

a baffle whose longitudinal axis is disposed at substantially right angles to the tubes.

Figure 10 is a similar view, showing a baffle disposed at right angles to the tubes and constructed from tile or blocks whose top and bottom faces are disposed at right angles to the front and rear faces of the tile.

Figure 11 is a view similar to Figure 7, showing how the tile or blocks can be arranged so as to produce a baffle whose longitudinal axis is disposed at an angle greater than the average angle or conventional angle; and

Figure 12 is a view similar to Figure 7, showing how the tile or blocks can be arranged so as to produce a baffle whose longitudinal axis is disposed at an angle less than the average angle or conventional angle.

In the accompanying drawings which illustrate the preferred form of my invention, A designates a tile or block that is adapted to be used to form the intermediate portion of a baffle or wall through which tubes 1 or other devices extend, and B and C designate end tile or blocks that are adapted to be used to form the end portions of said baffle. Each of said tile consists of a member, usually formed of refractory material, provided in some of its faces with cut-outs or recesses that form portions of the tube holes in the baffle. Said tile can be of various shapes and sizes, and can be designed so that they can be arranged either horizontally or vertically in the baffle of which they form a part. Usually, said tile will be arranged in horizontal courses and cut-outs or recesses will be formed in the top and bottom faces of same, so as to form holes through which the tubes pass. In the preferred form of my invention, as herein illustrated, each of the intermediate tile A co-operates with or contacts with three tubes disposed in triangular relationship, but it will be obvious that said tile can be made longer, so as to co-operate with a greater number of tubes. If desired, said tile can be designed so that they can be arranged vertically in the tube bank.

As shown in Figure 4, the intermediate tile A is provided on one of its horizontal faces with a semi-circular-shaped recess 2, that forms one-half of a tube hole, and it is provided on its other horizontal face with two segmental-shaped recesses 3, each of which forms one quarter of a tube hole, the recess 2 being arranged intermediate the recesses 3. The vertical front and rear faces of said tile are disposed at right angles to its top and bottom faces, so that when a plurality of such tile are arranged edgewise to form superimposed, horizontal courses, as shown in Figure 3, the recesses 2 in the top faces of the tile that constitute one horizontal course will co-operate with the recesses 3 in the bottom faces of the tile of the next higher horizontal course to form tube holes

4. Each end tile B is provided on its top face with a semi-circular-shaped recess 2^a and in its bottom face with a segmental-shaped recess 3^a arranged at the inner corner of the tile, and each end tile C is provided in its bottom face with a segmental-shaped recess 3^b located at its inner corner. The top and bottom faces of the tile A, B and C can either be disposed at an acute angle with relation to the front and rear faces of said tile, as shown in Figures 3 and 7, or the top and bottom faces of said tile can be disposed at substantially right angles to the front and rear faces of the tile, as shown in Figure 10. Preferably, the intermediate tile and the end tile are provided with top and bottom faces disposed substantially at an acute angle relatively to their front and rear faces, so that when said tile are laid up in longitudinal alignment with each other, as shown in Figure 7, they will form a straight, smooth-faced baffle whose longitudinal axis is disposed at the average angle or conventional angle with relation to the tubes 1 that pass through the baffle.

The principal feature which distinguishes my tile from the tile of this general type which have heretofore been used in the construction of boiler baffles, is that it is provided with means that enables it to be interlocked with co-operating tile arranged either in alignment, in offset relation, or in reversed relation with same. Various means can be used for accomplishing this highly desirable result, but I prefer to provide the top and bottom of each tile with a plurality of ribs 5 and grooves 6 that extend lengthwise or longitudinally of the tile, and which are adapted to mesh or interlock with the ribs and grooves on adjacent tile. By constructing the tile in this manner I produce a universal tile that can be used to form baffles of various shapes or baffles which are disposed at various angles to the tubes that pass through the baffles, simply by changing the relationship between the tile of the respective courses. Moreover, the co-operating corrugated portions on the tile produce joints between the tile that are substantially gas-tight, as each joint comprises a plurality of interlocked ribs that are disposed transversely of the path which the gases must travel in passing through the joint between adjacent tile.

If the baffle that is to be constructed consists of a straight baffle arranged transversely of the tube bank and disposed approximately at an acute angle to the tubes, as shown in Figure 1, the intermediate portion of the baffle is formed from tile A arranged in horizontal courses with the front and rear faces of the tile of each course extending flush with each other, as shown in Figure 7, and the end portions of the baffle are formed from end tile B and C, the corrugations

formed by the ribs 5 and grooves 6 on the top and bottom faces of the tile serving to interlock said tile with each other and also form substantially gas-tight joints between the horizontal faces of the tile of adjacent horizontal courses. If desired, the end faces of the tile can be provided with corrugations, as shown in Figure 4^a, so as to form substantially gas-tight joints between the tile 10 constituting each horizontal course, the ribs and grooves that constitute said corrugations being preferably disposed at right angles to the axis of the boiler tubes. When tile of the design shown in Figures 4, 5 and 6 are used, the vertical joints of the respective course will be arranged in staggered relation, as shown in Figure 3.

If it is desired to construct a baffle y provided with a curved portion, as shown in Figure 2, the tile in the respective horizontal courses that constitute the curved portion of the baffle are arranged in offset relation, as shown in Figure 8, so as to produce a baffle whose front side approximates a curve 25 represented by the broken line y' . This, of course, is made possible by reason of the fact that the top and bottom faces of the tile are provided with corrugated portions of the same shape and dimensions that mesh with each other, and which are of sufficient area 30 to insure the various courses being held in operative relationship, both when they are in alignment and in offset relation. By offsetting the respective courses more or less, the 35 curvature of the baffle can be easily changed.

If it is desired to produce a baffle whose longitudinal axis is substantially straight and disposed at an angle greater than the average angle or conventional angle represented by the baffle shown in Figure 7, the tile of the respective courses are offset rearwardly slightly, as shown in Figure 11, thus producing a baffle whose front face, represented by the broken line y^2 in Figure 11, is inclined 40 at a greater angle than the front face of the baffle shown in Figure 7. To produce a baffle whose longitudinal axis is disposed at an angle less than the average angle or conventional angle, the tile of the respective courses 45 are offset forwardly slightly relatively to each other, as shown in Figure 12, thereby producing a baffle whose front face, represented by the broken line y^3 , is inclined at a less angle than the front face of the baffle 50 shown in Figure 7.

In constructing a baffle z whose longitudinal axis is disposed at right angles to the tubes, as shown in Figures 1 and 2, tile of the kind shown in Figure 10 can be used, or tile 55 of the kind shown in Figure 7, can be used if the tile in alternate courses are arranged in reversed relation, as shown in Figure 9, the co-operating ribs and grooves 5 and 6 on the horizontal faces of the tile being of such shape that they will mesh properly and

produce substantially gas-tight joints between the tile of the respective horizontal courses, when the tile of the respective courses are arranged so that the front and rear faces of same are disposed in parallel relation, and when the tile of the respective courses are arranged so that the front and rear faces of same are disposed in angular relationship. 70

It will thus be seen that a tile, block or member of the construction above described overcomes the necessity of using special tile for each baffle of a particular shape or angle. Moreover, when tile or members of the construction above described are being laid up to form a wall or baffle, the shape of the baffle or the angle of same can be changed easily, 75 simply by adjusting the tile of the respective courses, so as to arrange them in offset relation or in reversed relation. Moreover, a baffle or wall constructed from such tile is substantially gas-tight, as the co-operating portions on the tile which hold the tile in adjustable, interlocking relation, are of such design that they form tortuous joints between the tile that effectively prevent gases 80 from passing through said joints. 90

Having thus described my invention, what I claim as new and desire to secure by Letters Patent is:

1. A baffle or wall composed of members 95 having co-operating spaces adapted to receive devices which pass through the wall and provided with co-operating interlocking portions constructed to permit the adjacent members to be arranged either in alignment 100 or in offset relation with each other so as to vary the shape or angle of the front and rear faces of the wall.

2. A baffle or wall composed of members having co-operating spaces adapted to receive devices which pass through the wall and provided with co-operating interlocking portions constructed to permit the adjacent members to be arranged either in alignment, in 105 offset relation or in reversed relation with 110 each other so as to vary the shape or angle of the front and rear faces of the wall.

3. A baffle or wall provided with openings for receiving devices that pass through said wall, said wall being composed of courses 115 or rows of tile or similar members provided with means that interlocks the adjacent tile together and permits the adjacent tile to be arranged either in alignment or in offset relation with each other so as to vary the shape 120 or angle of the front and rear faces of the wall.

4. A baffle or wall composed of tile having co-operating spaces adapted to receive devices which pass through the wall and provided with interlocking corrugated portions, constructed so as to permit adjacent tile to be arranged either in alignment or in offset relation with each other so as to vary the shape or 125 angle of the front and rear faces of the wall 130

and also to effectively prevent gases from passing through the joints between the interlocked portions of said tile.

5. A baffle or wall composed of rows of tile having co-operating spaces adapted to receive devices which pass through the wall and members provided on some of their faces with grooves and ribs disposed at substantially right angles to said devices, so as to form interlocked corrugated portions on said faces of sufficient area to permit the adjacent tile to be arranged either in alignment or in offset relation with each other to vary the shape or angle of the front and rear faces of the wall.

6. A baffle or wall made up of tile provided on some of their meeting faces with recesses that constitute openings for devices which pass through the wall, the said faces of said tile having co-operating interlocking portions constructed so as to prevent gases from circulating through the joints between adjacent tile and also permit the tile to be arranged in various positions with relation to each other so as to change the shape or angle of the front and rear faces of the wall.

7. A baffle or wall composed of tile arranged to form a plurality of courses or rows, said tile being provided with co-operating recesses that form openings for devices which pass through the wall, and interlocking corrugated portions on the meeting faces of said tile, disposed transversely of the devices which pass through the wall, and being of sufficient area to permit the tile to be arranged in offset relation, so as to vary the shape or angle of the front and rear faces of the wall.

8. In a structure of the kind described, the combination of a bank of water tubes, a baffle arranged transversely of said tube bank and made up of tile having spaces through which the tubes pass, and co-operating interlocking portions on adjacent tile constructed so as to permit of an adjustment of the tile longitudinally of the tubes, so as to vary the shape or angle of the front and rear faces of the baffle.

9. In a structure of the kind described, the combination of a bank of tubes, a baffle arranged transversely of the tube bank and made up of tile having spaces through which the tubes pass and co-operating interlocking portions on the top and bottom faces and end faces of said tile that form gas-tight joints between the same and which permit adjacent tile to be adjusted relatively to each other, for the purpose described, in the operation of constructing the baffle.

10. In a structure of the kind described, the combination of a tube bank, a baffle arranged transversely of the tube bank and composed of tiles having spaces through which the tubes pass, each of said tiles consisting of a member provided with top and bottom faces disposed at an angle to the front and rear faces of the

member, and interlocking corrugations on the top and bottom faces of said tile disposed longitudinally of the tile and being of sufficient area to mesh with each other when adjacent tile are arranged in offset relation to each other to vary the shape or angle of the baffle.
